[57] CLAIM

The ornamental design for a stall partition for stall barns, as shown in the accompanying drawings.

DESCRIPTION

FIG. 1 is a side elevational view of the stall partition for stall barns;

FIG. 2 is a right end elevational view of the stall partition for stall barns;

FIG. 3 is a left end elevational view of the stall partition for stall barns;

FIG. 4 is a side elevational view of the forward bar section of the stall partition for stall barns;

FIG. 5 is a right end elevational view of the forward bar section;

FIG. 6 is a left end elevational view of the forward bar section;

FIG. 7 is a side elevational view of the rear bar section of the stall partition for stall barns;

FIG. 8 is a right end elevational view of the rear bar section;

FIG. 9 is a left end elevational view of the rear bar section;

FIG. 10 is a side elevational view of the left hand connecting member for connecting the rear bar section to the vertical support post of the stall partition for stall barns, the right hand connecting member having the same shape;

FIG. 11 is a right end view of the connecting member; and

FIG. 12 is a left end view of the connecting member.

Fig. 1.

Fig. 2.

Fig. 3.

Fig. 4.

Fig. 5.

Fig. 6.

Fig. 7.

Fig. 8.

Fig. 9.

Fig. 10.

Fig. 11.

Fig. 12.

UNITED STATES PATENT AND TRADEMARK OFFICE
CERTIFICATE OF CORRECTION

PATENT NO. : Des. 297,469

DATED : August 30, 1988

INVENTOR(S) : Kjell Johansson

It is certified that error appears in the above-identified patent and that said Letters Patent is hereby corrected as shown below:
